UNITED STATES PATENT OFFICE.

GEORGE FRANCIS PURSER, OF SARNIA, CANADA.

DESIGN FOR A GAME-TABLE.

SPECIFICATION forming part of Design No. 33,395, dated October 16, 1900.

Application filed June 18, 1900. Serial No. 20,776. Term of patent 7 years.

To all whom it may concern:

Be it known that I, GEORGE FRANCIS PURSER, a citizen of the Dominion of Canada, residing at Sarnia, in the county of Lambton and 5 Province of Ontario, Canada, have invented and produced a new and original Design for a Game-Table, of which the following is a specification, reference being had to the accompanying drawings, forming part thereof.

Figure 1 is a perspective view of a game-table, showing my new design. Fig. 2 is a sectional view taken on the longitudinal center.

As shown in the drawings, the leading or material feature of my new design consists of 5 a horseshoe-rim A, Fig. 1, connected at the heel by a curved tie B, Fig. 1, inclosing the bottom C, Fig. 1. The rim A is perforated,

as shown at D, Fig. 1. The rim also contains four recesses, as shown at E, Fig. 1. The whole is supported by three calkers of the 20 horseshoe-rim A, as shown at G, Fig. 1.

Having described my invention, what I claim to be new, and desire to secure by Letters Patent, is—

The design for a game-table, substantially 25 as shown and described.

In testimony whereof I have signed my name to this specification in the presence of two subscribing witnesses.

GEORGE FRANCIS PURSER.
